HAND-OPERABLE BELT SANDER

Frank J. Kuenzl, Deerfield, Ill., assignor to Skil Corporation, Chicago, Ill., a corporation of Delaware

Filed Oct. 3, 1960, Ser. No. 62,328

Term of patent 14 years

(Cl. D37—1)

Fig. 1

*Fig. 3**Fig. 4**Fig. 5*Fig. 1 is a perspective view looking toward one side of a hand-operable belt sander showing my new design;

Fig. 2 is a slightly reduced top plan view thereof;

Fig. 3 is a slightly reduced side elevational view showing the opposite side of the belt sander from that shown in Fig. 1;

Fig. 4 is a slightly reduced front end elevational view thereof; and

Fig. 5 is a slightly reduced rear end elevational view thereof.

I claim:

The ornamental design for a hand-operable belt sander, substantially as shown.
